United States Patent Office

Des. 214,257
Patented May 27, 1969

214,257

BOY'S APRON

Marvin I. Glass and Patricia M. Jackson, Chicago, Ill.,
assignors to Marvin Glass & Associates, Chicago, Ill.,
a partnership

Filed Mar. 12, 1968, Ser. No. 10,935

Term of patent 14 years

Int. Cl. D2—01

U.S. Cl. D2—228

FIGURE 1 is a perspective front view of a boy's apron showing our new design; and

FIGURE 2 is a rear plan view of the apron, reduced in scale.

The dotted line showing of items held in the apron is for illustrative purposes only.

We claim:

The ornamental design for a boy's apron, substantially as shown and described.
